UNITED STATES PATENT OFFICE.

FRANK J. HABURCAK, OF CLEVELAND, OHIO.

CRADLE MOTOR.

Application filed September 23, 1926. Serial No. 187,054.

This invention has for its object the provision of an operating mechanism which will be compact and especially adapted to be disposed under a rocking crib body and within the lines of the supporting frame so that it will be protected against derangement from chance blows, and will act automatically to propel the cradle in opposite directions whereby to import oscillation thereto and will continue to operate as long as desired. Other incidental objects of the invention will appear in the course of the following description, and the invention resides in certain novel features which will be particularly pointed out in the appended claim.

In the accompanying drawings:

Fig. 1 is an enlarged longitudinal section through the motor;

Fig. 2 is a perspective view of the motor with the circuits for operating the same shown diagrammatically;

Fig. 3 is a detail sectional elevation of one end of the push rod, and

Fig. 4 is a detail perspective of the movable circuit closer.

The motor is carried by the cradle-supporting frame adjacent one end thereof and comprises two solenoids or magnets 11 and 12, and a push rod 13 which constitutes the core of the said magnets and is disposed axially thereof. The ends of the push rod 13 are constructed with sockets 14 to receive the inner ends of plungers 15, a spring 16 being seated in each socket 14 and bearing at its opposite ends respectively against the inner end of the plunger and the bottom of the socket, as clearly shown in Fig. 3. The outer end of each plunger presses against a brace 17 forming a part of the cradle body and a metallic wear plate 18 is preferably secured upon the inner face of the brace whereby to minimize wear due to the pressure and movement of the plunger. It will be understood that to rock the cradle a reciprocatory motion is imparted to the push rod so that it will press against the opposite braces 17 alternately and thereby push the cradle alternately in opposite directions, and the springs 16 serve to maintain the contact

while at the same time yielding to the reversal of movement so that noisy shock will be avoided. The push rod or core is carried by grooved rollers 19 whereby it is guided and held to a rectilinear path, and these 55 rollers are located adjacent the opposite ends of the motor. The rollers are carried by brackets 20 which are secured transversely to the upper beams 7 of the cradle-supporting frame and, as shown most clearly in 60 Fig. 2, may conveniently consist of flat bars or straps having their ends turned downwardly to pass at opposite sides of the core or push rod and terminating in eyes 21 supporting the axles 22 of the rollers. Blocks 65 23 are secured upon the brackets 20 between the beams 7 and at opposite sides of the center of the brackets, which blocks are suitably insulated from the brackets, and carried by and disposed between the said 70 blocks is a frame 24 having sockets or open bearings 25 at its center upon its sides to receive the trunnions 26 extending from a movable switch or contact member 27. The lower end of this switch is disposed obviously 75 between the magnets or solenoids 11 and 12 and will rest upon or be disposed in the path of a piston 28 secured upon the push rod at the center of the same. The trunnions 26 are located somewhat above the 80 center of the switch or circuit closer 27 so that the weight thereof will tend to hold it in a perpendicular position and, therefore, if the piston 28 be moved to either side of the central vertical plane of the space between 85 the magnets, the circuit closer will swing into a vertical position with its end below the high point of the piston and in the path of the same. Consequently, when the piston is moved toward the movable contact member or switch 27, the end of the piston will impinge against the end of the switch and rock the same, as will be understood on reference to Fig. 1. The movement of the plunger continues until it clears the 95 switch, whereupon the weight of the switch will return it to its vertical position breaking the circuit and de-energizing the magnet.

Upon each block 23 are secured spaced 100

contacts 29 and at the upper end of the switch 27 is a cross bar 30 which, when the switch is rocked to the limit of its movement, will bridge the adjacent contacts and close the circuit through the same. The magnets are suspended from the brackets 29 by angle plates 31 which are secured to the ends of the magnets and to the brackets respectively, as shown clearly in Fig. 1.

Referring now more particularly to Fig. 2, it will be noted that two of the contacts 29 are connected electrically by a conductor 32 and one conductor 33 of the leading-in cable 34 is connected by branches 35 with the respective windings of the solenoids or electro-magnets. The opposite end of the magnet 11 is connected by a conductor 36 with a contact 29 located over the magnet 12 and the magnet 12 is, in turn, connected by a conductor 37 with the contact 29 over the magnet 11, while the conductor 38 of the leading-in cable is connected with one of the contacts 29 to which is secured one end of the conductor 32. Assuming the parts to be in the position shown in Figs. 1 and 2, it will be noted that the electric current passes over the conductor 38 to the forward contact 29 at the right of the drawings, thence through the conductor 32 to the forward contact 29 at the left of the drawings and then through the circuit closing member 30 to the companion contact 29 whence it flows through the conductor 37 to the magnet 12, through the winding of said magnet and out through the conductors 35 and 33, thereby energizing the magnet and causing the push rod or core to move to the right in the drawings, and swing the cradle body in the same direction. As soon as the piston 28 carried by the push rod or core clears the lower end of the switch 27, the switch will swing to a vertical position and the circuit will be thereby broken because the bridging contact 30 will be moved from the corresponding contacts 29. The momentum of the cradle body, however, will continue momentarily and then the weight of the cradle body will reverse its movement and will effect initial reverse travel of the push rod. The reverse travel of the push rod will, of course, cause the piston 28 to impinge against the lower end of the switch 27 and swing the contact member 30 over into engagement with the contacts 29 at the right of the drawings, whereupon the current will flow from the front contact 29 at the right through the contact 30 to the contact 29 in rear thereof and thence through the conductor 36 to the magnet 11 and pass from the said magnet through the conductors 35 and 33. The magnet 11 will thus be energized and will carry the core or push rod beyond the central vertical plane of the apparatus so that the movement of the cradle body will be continued and it

will not be permitted to come to rest. The circuit will again be automatically broken at the right of the drawings and then closed at the left and this alternate movement will continue as long as the current is permitted to flow to the motor. For convenience, the leading-in wires may be connected to a switch which, in turn, will be connected with the house circuit in a well known manner by the use of extension cords or conductors.

From the foregoing description, taken in connection with the accompanying drawings, it will be seen that I have provided a very simple, compact and inexpensive mechanism which may be readily applied to a cradle and which will operate automatically to impart oscillation to the cradle.

Having thus described the invention, I claim:

The combination of a pair of axially aligned solenoids, a push rod extending through and constituting a core for the solenoids and having its ends in engagement with a member to be oscillated, pairs of contacts arranged adjacent the opposed ends of the respective solenoids and disposed in planes transverse to the solenoids, one contact over each solenoid being electrically connected with a terminal of the other solenoid and the other contacts being electrically connected with each other, leading-in conductors one connected with one of the last-mentioned contacts and one connected with the terminals of the solenoids, a support between the pairs of contacts, a switch member disposed between the pairs of contacts and provided with lateral trunnions journaled on said support, the switch member having a cross bar at its upper end and having its lower end adjacent the push rod, and a piston on the push rod arranged to impinge against and ride under the lower end of the switch member to rock said member and cause the cross bar thereon to bear against and bridge either pair of contacts whereby to energize the solenoids alternately.

In testimony whereof I affix my signature.

FRANK J. HABURCAK. [L. S.]
